Primary Examiner — Dana K Weiland*Assistant Examiner* — Emily Anna Saunders(57) **CLAIM**

The ornamental design for a weight lifting platform, as shown and described.

DESCRIPTION

FIG. 1 is a front right perspective view of a weight lifting platform showing my new design;

FIG. 2 is a bottom right perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The evenly dashed broken lines depict portions of the weight lifting platform in which the design is embodied that form no part of the claimed design.

The dot-dash broken lines are for defining the bounds of the claimed design only and form no part of the claimed design.
